O. B. WOODROW

RACK FOR OPERATING MECHANISM FOR WASHING MACHINES

Filed Oct. 16, 1923

Inventor
Q. B. Woodrow
by Dilling & Haeger Att'y's.

UNITED STATES PATENT OFFICE.

OLIVER B. WOODROW, OF NEWTON, IOWA.

RACK FOR OPERATING MECHANISM FOR WASHING MACHINES.

Application filed October 16, 1923. Serial No. 668,837.

To all whom it may concern:

Be it known that I, OLIVER B. WOODROW, a citizen of the United States, and a resident of Newton, in the county of Jasper 5 and State of Iowa, have invented a certain new and useful Rack for Operating Mechanism for Washing Machines, of which the following is a specification.

In connection with the use of so-called 10 dolly type domestic washing machines it is customary to impart an alternating rotary motion to the dolly by means of a pinion connected to the dolly shaft above the washing machine cover and a rack bar normally 15 in mesh with the pinion but capable of being swung to position away from the cover and out of mesh with the pinion. These rack bars are ordinarily made of cast metal and comparatively heavy and with the devices 20 now in common use there has been considerable loss due to breakage of the rack bars when they are permitted to drop outwardly and downwardly when disengaged from the pinion, and furthermore, they have 25 caused considerable danger due to accidental pinching of the fingers and hands of the operator.

My object is to provide a gearing device 30 of this connection of simple, durable and inexpensive construction and which, when the cover is open, will first automatically disengage the rack bar from the pinion and then as the cover is swung to open position, the rack bar will be automatically retained 35 in a substantially upright position by the cover so that it cannot fall outwardly and downwardly.

A further object is to provide a device 40 of this character in which when the cover is swung to a closed position, the rack will automatically assume a position in mesh with the pinion.

A further object is to provide a device 45 of this character in which the rack and pinion are so protected that an operator's fingers cannot become caught therein.

My invention consists in the construction, 50 arrangement and combination of the various parts of the device, whereby the objects contemplated are attained, as hereinafter more fully set forth, pointed out in my claims,

and illustrated in the accompanying drawings, in which:

Figure 1 shows a side elevation of a part 55 of a washing machine body with a cover thereon, and my improved rack bar controlling device applied thereto.

Figure 2 shows a top or plan view of same 60 with the cover in a closed position and a portion of the gear case and the top of the rack bar broken away to show the intermeshing gears.

Figure 3 shows a side elevation of a part 65 of a washing machine body with a hinged cover thereon slightly elevated, illustrating the position of the rack bar as it commences to disengage the pinion.

Figure 4 shows an enlarged detail sectional view 70 illustrating the rack bar and pinion with the rack teeth in position to enter between the toothed spaces on the pinion; and

Figure 5 shows a transverse sectional view 75 of the rack bar and guide plate on the line 5-5 of Figure 2.

Referring to the accompanying drawings I have used the reference numeral 10 to indicate that portion of the washing machine body shown and 11 is the hinged cover. Mounted on one side of the washing 80 machine body is a bracket 12 in which a lever 13 is mounted to stand in a substantially vertical position. Pivoted to the top of the lever 13 is a rack bar proper indicated by the numeral 14. Mounted within 85 the cover 11 is a dolly shaft 15 upon which a dolly 16 is mounted, and on the shaft 15 is a pinion 17. All of these parts are of the ordinary construction now in common use.

My improvement consists in providing on 90 top of the cover 11 a guide plate 18 having guide ribs 19 extended upwardly therefrom and spaced apart from each other. Pivoted in the outer end of this guide plate is a 95 rack engaging loop 20 which normally rests by gravity on top of the ribs 19. The rack bar is formed with an extension at its free end, which extension is tapered and forms a finger 21 which normally rests on the guide 100 plate 18 between the ribs 19 and is of such size that it will pass under the rack engag-

ing loop 20. The lower portion of this finger 21 is provided with a rounded downwardly extended portion 22 which rides upon the top of the guide 18.

5 The rack bar proper at the portion thereof which contains the teeth is formed with a solid side member 23 and a solid top member 24, and the rack teeth are formed integral with these side and top members. The 10 lower edges of the rack teeth are tapered or rounded at 25, as clearly shown in Figure 4. Otherwise, they are shaped in the customary manner for rack bar teeth.

Mounted upon the top of the cover member 11 is a gear case 26 to enclose the pinion except for the side adjacent to the rack bar. This gear case is provided with protecting wings 27 which lie alongside that portion of the rack bar that is provided with teeth.

20 Said wings are extended to such positions that they will completely cover the adjacent face of the rack bar teeth when the rack bar is in any position of its normal movement.

I have also provided a guide roller 28 mounted on the cover member 11 adjacent to the pinion and designed to engage the face of the rack bar opposite from the pinion and in order to prevent the person's fingers or other objects from becoming 30 pinched between the adjacent surfaces of the rack bar and the said guide roller, I have provided substantially triangularly shaped lugs 29 fixed in position on the cover.

35 In practical operation and during the normal movement of the rack bar to agitate the dolly, the rack bar is reciprocated and slides within the guide 19 in mesh with the pinion and imparts an alternating rotary movement to the dolly shaft. If at any time the cover is opened, then the rack bar will slide in along the guideway between the guide ribs 19 with the fingers 21 in the groove formed by said ribs. The downwardly projecting rounded portion 22 of the fingers will act as a fulcrum tending to elevate the rack teeth out of the pinion. Hence, the first effect of the movement of 45 opening the cover will be to automatically disengage the rack bar from the pinion.

50 As the cover is further opened, the fingers 21 will pass under the loop 20 and then when the cover is swung to position past a vertical line, the loop will hold the rack bar 55 against further outward movement, as illustrated in Figure 1. When the cover is returned to a closed position, the rack bar will descend and the rounded or tapered lower ends 25 of the rack teeth will freely enter

60 the two spaces of the pinion, and will be guided by the fingers 21 to position between the pinion and the roller 28, and obviously when the cover is closed, there is no portion of the rack or pinion that is exposed in any 65 such manner as to make it possible to pinch

the operator's fingers or garments upon the top of the cover.

I claim as my invention:

1. In a device of the class described, the combination of a body, a hinged cover 70 thereon, a pinion supported by the hinged cover, a rack bar pivotally supported at the side of the body beyond the hinged point of the cover, and a loop pivoted to the cover normally lying in the path of 75 the rack bar, said parts being so arranged and proportioned that when the cover is being opened, the end of the rack bar will pass under said loop, and when the cover is swung to open position past a vertical 80 line, the rack bar will be held by said loop against further outward movement relative to the cover, for the purposes stated.

2. In a device of the class described, the combination of a body, a hinged cover 85 thereon, a pinion supported by the hinged cover, a rack bar pivotally supported at the side of the body beyond the hinged point of the cover, a tapered finger having a rounded lower end formed on the rack bar, 90 a guide device having a groove therein in which said finger is slidably mounted, and a loop pivoted to the cover above said groove, for the purposes stated.

3. In a device of the class described, the 95 combination of a body, a hinged cover therefor, a rack bar pivotally supported beyond the hinged center of the cover, the outer end of the rack bar being formed with a finger having a downwardly extended rounded portion, a guide on the cover upon which 100 said finger normally rests, rack bar teeth formed on the rack bar, the lower ends of the teeth being arranged in a plane slightly above the lower portion of said finger, and the lower ends of said teeth being tapered, 105 for the purposes stated.

4. In a device of the class described, the combination of a body, a hinged cover thereon, a pinion mounted in the cover, a rack 110 bar pivotally supported at one end beyond the hinged center of the cover, said rack bar being formed with a smooth top and outer side members and being formed with rack teeth exposed on the other side member 115 and the bottom, a gear case for the pinion, and wings secured adjacent to the gear case and being extended to positions where they will cover the exposed sides of the rack teeth when the rack is in any position of its 120 normal movement relative to the pinion.

5. In a device of the class described, the combination of a body, a hinged cover thereon, a pinion mounted in the cover, a rack 125 bar pivotally supported at one end beyond the hinged center of the cover, said rack bar being formed with a smooth top and outer side members and being formed with rack teeth exposed on the other side member and the bottom, a gear case for the pinion, 130

and wings secured adjacent to the gear case and being extended to positions where they will cover the exposed sides of the rack teeth when the rack is in any position of its 5 normal movement relative to the pinion, and a guide normally mounted upon the cover adjacent to the pinion and designed to en-

gage the smooth side of the rack bar, and substantially triangular protecting blocks arranged between the sides of said roller and 10 the adjacent side of the rack bar, for the purposes stated.

Des Moines, Iowa, September 8, 1923.

OLIVER B. WOODROW.
